UNITED STATES PATENT OFFICE.

THOMAS P. FLYNN, OF ST. CLOUD, MINNESOTA.

CARTRIDGE-LOADING MACHINE.

SPECIFICATION forming part of Letters Patent No. 629,029, dated July 18, 1899.

Application filed April 22, 1898. Serial No. 678,469. (No model.)

To all whom it may concern:

Be it known that I, THOMAS P. FLYNN, a citizen of the United States, and a resident of St. Cloud, Stearns county, State of Minnesota, have invented certain new and useful Improvements in Machines for Loading Cartridges; and my preferred manner of carrying out the invention is set forth in the following full, clear, and exact description, terminating with claims particularly specifying the novelty.

This invention relates to machines known as "cartridge-loaders;" and the object of the same is to produce certain improvements therein.

To this end the invention consists in the details of construction hereinafter more fully described and claimed and as illustrated in the accompanying drawings, wherein—

Figure 1 is a plan view of this machine complete, but with the cover of the magazine removed. Fig. 2 is a right-side elevation, partially broken away, showing the parts in the act of delivering a charge. Fig. 3 is a transverse section on the line 3 3 of Fig. 1 looking in the direction of the arrows. Fig. 4 is a section through the charger, illustrating the means for adjusting the size of the charge. Fig. 5 is a section through the supporting-post, showing details of the clutch mechanism. Fig. 6 is a detail showing the base of the magazine in plan view with the hopper removed. Fig. 7 is a detail illustrating the members of the charger and showing means for adjusting the size of the charge.

Referring to the said drawings, the letter *a* designates a base of approximately circular form and having an extension at one side, from which rises a bracket *b*⁴, whose upper end extends forward in an arm over the center of the base and is bifurcated, as seen in Fig. 8, its cross-sectional shape being best seen in Fig. 3.

*b*¹ is the bed, preferably supported on roller bearings *a*² in the base and surmounted by a shell-holder *b*³, having a removable top *b*⁵. The shell-holder is hooked to the bed, as at *b*⁴ in Fig. 4, and interiorly it has upright partitions *b*⁶, forming chambers for the shells, which partitions are continued upward, as at *b*⁶, in the top piece *b*⁵ and preferably beveled off at the upper ends of the chambers. The

bed *b*¹ is mounted on a post *c*, which projects downward and has a flange *c*⁸, (see Fig. 5,) which flange and the lower end of the post 55 may be supported by ball-bearings *a*³ in the base *a*. The flange is exteriorly provided with notches *c*¹⁰, which are engaged by the tip of a spring-dog *c*⁹, and these notches are spaced from each other a distance which will 60 bring all the shell-chambers step by step under a given point, for which purpose it will be understood that the chambers in the various concentric circles of the shell-holder *b*³ are always equidistant from each other. 65

While any approved means may be employed for rotating the shell-holder step by step over the base, I prefer the mechanism herein illustrated. This consists of a clutch-ring *c*¹, surrounding the post *c* loosely and 70 having oblique openings *c*²⁰ in its inner face, in which are mounted rollers or balls *c*². From one side of the ring projects an arm *c*⁷, to which at the point *c*⁴ is pivoted a link *c*³. The latter extends out through the side of the base 75 and is drawn normally outward by a spring *c*⁸, preferably located within the bracket *b*⁴.

*c*⁵ is an L-shaped lever pivoted at *c*⁶ near its angle within this bracket, its lower end being engaged with the link *c*³ and its upper 80 end projecting forwardly over the bracket-arm *b*⁴, as shown. By this construction each time the forward end of the lever *c*⁵ is raised its lower end pushes on the link *c*³, which turns the ring *c*¹ preferably in a direction to 85 clutch the balls *c*² between the oblique walls of the openings *c*²⁰ and the exterior of the post *c*. Continued movement then turns the post one step or until the tip of the spring-dog engages the next notch *c*¹⁰, and another 90 cartridge-shell is therefore brought in position for treatment. It will be obvious that by inverting the clutch-ring exactly the opposite motion will take place, and an inward push on the link *c*³ will then open the clutch, 95 and the return movement under the force of the spring *c*⁸ will cause the rotation of the shell-holder *b*³.

My invention contemplates the removable application to the bracket-arm *b*⁴ of mechanism for charging the shells, for ramming the charge, and finally for crimping the shells, each of which mechanisms is provided with means for moving the actuating-lever at every

operation, so as to turn the shell-holder in the manner just described.

It will be obvious that the size of the shell-holder and the number of chambers therein are dependent only upon the capacity of the machine and the rigidity of the parts, and I have found that a machine with one hundred such chambers can be built and successfully operated.

10 The charging mechanism is mainly illustrated in Figs. 1, 2, and 3. On the bracket-arm b^4 move two guides d^{10} , through one of which may be passed a set-screw d^9 . These guides are at the bottom of a cup-shaped magazine-base d , through which bottom hangs a discharge-tube d^8 at the forward side of said base and in position to stand between the two arms b^4 . From the center of this base rises a post d^2 , on which is journaled the inner end 15 of a lever d^4 , whose body projects outward through a slot d^{10} (here shown at the right side of the base) and carries a handle. At the other side of the post d^2 , opposite the handle, the lever carries a cam d^3 , so shaped that its 20 lower end normally stands under the forward end of the actuating-lever c^5 , which projects loosely through an upright slot d^{50} in the rear of the base d , all as best seen in Fig. 6. Hence a movement of the handle d^4 from the 25 position therein shown and through a quarter of a circle will cause the cam d^3 to raise the front end of the lever c^5 , with the result described above.

The letter e designates the magazine proper 30 closed by a removable cover e^6 and whose bottom is interiorly conical, as at e^4 , and provided with a socket to fit removably over the post d^2 . Within the magazine is an upright partition e^7 , dividing it into shot and powder 35 compartments, and around the base of the cone are openings e^2 , communicating with said compartments and preferably closed by dampers e^3 , capable of operation from the exterior, 40 as shown. The lever d^4 within the magazine-base d carries the charger d^7 at a proper point to come under the openings e^2 in the bottom of the hopper, and from this lever there projects to the rear a flat curved arm d^6 , serving 45 as a closer-plate for each opening after the charger has moved away from beneath it. In 50 Fig. 7 it will be seen that the charger consists of concentric cylinders, of which the inner, d^7 , has a pin d^{70} and the outer, d^{11} , has an upright slot d^{75} with notches in one edge adapted 55 to engage this pin and is marked on its exterior with a scale along the outer edge of the slot. Hence the outer cylinder can be turned slightly on the inner, then adjusted longitudinally thereof, as desired, and finally again 60 turned to bring one of its notches into engagement with the pin d^{70} , thus adjusting the length of the complete charger by telescoping the outer cylinder more or less upon the inner.

d^{12} is the bottom of the outer cylinder, 65 which is provided at one edge with a depending pin d^{14} and from whose other edge rises its pivot-pin d^{13} , which passes through eyes

d^{30} on the exterior of the outer cylinder and is surrounded by a spring d^{31} , tending to hold the bottom normally closed. When the lever 70 d^4 is moved from the position shown in Fig. 6 around to the front to bring the charger over the discharge-tube d^8 , the pin d^{14} strikes the upper end of said tube and opens the charger, so that its contents fall through the 75 tube d^8 into the cartridge-shell beneath, and on the return movement the spring d^{31} throws the pivoted bottom back beneath the charger, and the closer d^6 meanwhile holds the opening e^2 closed until the charger again passes 80 beneath it, when a fresh charge of powder from the hopper will fall through the opening e^2 into the charger. The amount of powder received therein at this time is regulated by the adjustment of the length of the charger, 85 as above described, and in order that the upper end of the discharge-tube d^8 may always engage the pin d^{14} said tube is threaded, as at d^{80} , into the bottom of the magazine-base d . In this manner the charging of one row 90 of cartridge-shells in the shell-holder is performed, after which the entire magazine is adjusted longitudinally on the bracket-arm b^4 , the set-screw d^9 reset, and the charging of the next row of cartridge-shells is accomplished in the same manner, each movement 95 of the lever d^4 operating the actuating-lever c^5 in the manner described.

Obviously the shot is introduced into the shells upon the powder by turning the magazine a half-revolution on the post d^2 , the damper e^3 below the powder-compartment being closed and the other damper below the shot-compartment being opened.

All parts of this machine are of the desired 105 sizes, shapes, proportions, and materials, and considerable changes in and additions to the details of constructions herein set forth may be made without departing from the principle of my invention. It will be clear, for instance, that one of the compartments of the 110 hopper might contain shot and a second lever similar to d^4 could be provided at the opposite side of the post d^2 , but without a cam d^3 for moving the actuating-lever. Then the 115 charge of powder would be delivered by this second lever without moving the actuating-lever, and thereafter a charge of shot could be delivered by the lever shown in the drawings, which would move the actuating-lever 120 and turn the shell-holder one step. Of course provision is made for the insertion of the wads. Other changes and additions will suggest themselves to the skilled manufacturer 125 and can be readily made.

In operation the shell-holder b^4 is removed from the bed b' and loaded with shells from beneath. Then it is replaced and hooked in position and the top b^3 put on. The hopper is filled with powder, (or its compartments with powder and shot, as above described,) and the guides d^{10} are clamped at proper points on the bracket-arm b^4 to bring the discharge-tube d^8 over the outer row of shells. The 130

handle d^4 is then moved forward to charge one shell, as above described, and when returned the shell-holder turns forward one step. When the outer row of shells has been charged, the set-screw d^9 is loosened, the guides moved on the arm, and the set-screw reset to bring the discharge-tube over the second row of shells. As above described, the size of the charge can be regulated by the devices best seen in Fig. 7.

With a machine of this character a large number of shells can be rapidly charged, and while the operator is doing the work a boy can be removing the loaded shells from the holder last operated with and recharging it with empty shells for the next operation.

What I claim as new is—

1. In a cartridge-loading machine, the combination with a base having a bracket rising therefrom and provided with an arm extending over the base, a shell-holder mounted on the base and containing a ring of shell-chambers which latter are all equidistant from each other, mechanism for rotating said holder in steps equal to the distance between the centers of two contiguous chambers, and a lever for actuating such mechanism, which lever has one end over said bracket-arm; of a removable device for treating the shells, a guide therefor mounted on the bracket-arm, and an operating-lever whose movements trip the actuating-lever, as and for the purpose set forth.

2. In a cartridge-loading machine, the combination with a base having a bracket rising therefrom and provided with a longitudinally bifurcated arm extending over the base, a shell-holder mounted on the base and containing concentric rings of shell-chambers which latter are all equidistant from each other, mechanism for rotating said holder in steps equal to the distance between the centers of two chambers, and a lever for actuating such mechanism, which lever has one end over said bracket-arm; of a device for treating the shells, a guide therefor removably mounted on and longitudinally adjustable of the bracket-arm, and an operating-lever whose movement trips the actuating-lever, as and for the purpose set forth.

3. In a cartridge-loader, the combination with a shell-holder having concentric rings of shell-chambers, mechanism for imparting rotary movement to such holder in steps, a lever for actuating said mechanism, and a supporting-base having a bracket provided with a bifurcated arm extending over the holder; of a charging device consisting of a magazine and a base therefor, guides on the latter adjustable longitudinally on said bracket-arm, a discharge-tube depending from the base through the slot in said arm and capable of being moved by the adjustment of the base from a point above the center of the shell-chamber to a point above the outer ring of chambers therein, and mechanism for receiving a charge from the magazine-hopper and

delivering it through said tube, as and for the purpose set forth.

4. In a cartridge-loading machine, the combination with the loading mechanism proper; of the herein-described shell-holder, the same consisting of a base having supporting-rollers, a bed rotatably mounted on the rollers, a holder proper having concentric rings of upright shell-chambers all equidistant from each other, means for removably connecting the holder with its bed, and a removable top for the holder having interior partitions registering with those in the holder and beveled off at their upper edges, all as and for the purpose set forth.

5. In a cartridge-loading machine, the combination with a base, a spring-dog carried thereby, a shell-holder rotatably mounted on said base, a post journaled at its lower end in the latter and connected with the holder, and a flange fast on the post and having external notches engaged by said dog and corresponding with the distance between the shell-chambers in the holder; of a clutch-ring surrounding said post above its flange and having a lateral arm, clutches within the ring for binding the post when the ring is turned in one direction, a link pivoted to said arm and moved in one direction by a spring, and a lever for moving the link in the opposite direction, as and for the purpose set forth.

6. In a cartridge-loading machine, the combination with a base, a spring-dog carried thereby, a shell-holder rotatably mounted on said base, a post journaled at its lower end in the latter and connected with the holder, and a flange fast on the post and having external notches engaged by said dog and corresponding with the distance between the shell-chambers in the holder; of a clutch-ring surrounding said post and having oblique openings in its inner wall and a laterally-projecting arm, clutch balls or rollers within said openings adapted to bind the post when the ring is turned in one direction, a spring carrying said lateral arm in one direction, and an actuating-lever for moving it against the tension of its spring, as and for the purpose set forth.

7. In a cartridge-loader, the combination with a rotary shell-holder having a ring of shell-chambers, clutch mechanism for turning the holder in steps, a base supporting the holder and having an upright arm with a bracket, and a clutch-actuating lever pivoted within the arm and having one end extending over the bracket; of a charger mounted on the bracket, a horizontally-moving operating-lever therein, and a cam carried by said lever and standing under the upper end of said actuating-lever, as and for the purpose set forth.

8. In a cartridge-loader, the combination with a shell-holder having a ring of shell-chambers, means for rotating it in steps, and an actuating-lever for said means; of a magazine comprising a hopper and a base which latter has an upright slot through which said

actuating-lever projects, a delivery-lever moving horizontally in the base, and a curved cam carried by said delivery-lever and engaging beneath the actuating-lever, as and for the purpose set forth.

9. In a cartridge-loader, the combination with a shell-holder, a magazine comprising a hopper and a cylindrical base supported above the holder, the base having a slot in one side, a discharge-tube through the bottom of the base at one end of the slot, an outlet in the bottom of the magazine adjacent the other end of said slot, a lever pivoted at the center of the base and projecting through said slot, a charge-carrier supported by the lever and adapted to be moved from beneath the hopper-opening over the discharge-tube, said carrier comprising two telescopic cylinders of which the outer has an upright slot with notches in one edge and the inner has an outwardly-extending pin projecting through said slot and adjustably engaging said notches, and a curved closer-plate carried by said lever in rear of the charge-carrier, as and for the purpose set forth.

10. In a cartridge-loader, the combination with a cylindrical hopper comprising a base and a superimposed magazine, an upright partition dividing the latter into compartments each of which has an outlet-opening in its bottom, and a central socket in the bottom of the magazine; of a discharge-tube threaded through the bottom of the base, a post rising from the latter and on which said socket fits rotatably, a lever pivoted on said post, a vertically-adjustable charge-carrier on the lever adapted to move from under one of said outlet-openings over said discharge-tube, a closer-plate on the lever in rear of the carrier, a hinged bottom to said carrier, a projection thereon engaging the tube for opening said bottom when the carrier and tube are in alinement, and independent dampers for closing said outlet-openings, all as and for the purpose set forth.

11. In a cartridge-loader, the combination with a swinging lever, a hopper having a discharge-opening standing at one point and above the lever, and a base having a discharge-tube standing at another point and below the lever; of a charge-carrier supported

by the lever and consisting of telescoping cylinders, a pin on the exterior of the inner cylinder, the outer having an upright slot with notches in one edge adapted to engage said pin, a spring-closed bottom to the outer cylinder, and a pin pendent from the free edge thereof and adapted to strike the discharge-tube when the carrier is moved thereover, as and for the purpose set forth.

12. In a cartridge-loader, the combination with a swinging lever, a hopper having a discharge-opening at one point and above the lever, and a base having a vertically-adjustable discharge-tube standing at another point below the lever; of a charge-carrier supported by the lever and consisting of telescoping cylinders, means for holding them in adjusted position one on the other, eyes on the exterior of the outer cylinder, a horizontally-swinging bottom having an upright pivot-pin journaled in said eyes, a spring on this pin throwing the bottom normally closed, and a pendent pin at the free edge of the bottom adapted to engage the upper end of the discharge-tube when the carrier is moved thereover, as and for the purpose set forth.

13. In a cartridge-loader, the combination with a cup-shaped magazine-base having a ninety-degree slot in one side, a discharge-tube through its bottom at one end of the slot, a swinging lever pivoted at its center and projecting through said slot, a charge-carrier supported by the lever and adapted to be moved over said tube, and a closer-plate carried by the lever in rear of the carrier; of a concentric hopper mounted revolvably on the base and having a plurality of openings in its bottom either of which is adapted to be brought over the charge-carrier when in its normal position, a damper for each of said openings, a conical enlargement at the bottom of the magazine, and an upright partition across the center of the cone, as and for the purpose set forth.

In testimony whereof I have hereunto subscribed my signature on this 19th day of April, A. D. 1898.

THOMAS P. FLYNN.
